UNITED STATES PATENT OFFICE.

FRANK SPONG, OF GLENDALE, CALIFORNIA.

DIRIGIBLE HEADLIGHT.

1,327,574.

Specification of Letters Patent.

Patented Jan. 6, 1920.

Application filed June 17, 1919. Serial No. 304,944.

To all whom it may concern:

Be it known that I, FRANK SPONG, a citizen of the United States, residing at Glendale, in the county of Los Angeles and State 5 of California, have invented new and useful Improvements in Dirigible Headlights, of which the following is a specification.

My object is to make an improved dirigible headlight especially for Ford automobiles, and my invention consists of the 10 novel features herein shown, described and claimed.

Figure 1 is a fragmentary top plan view 15 of a Ford automobile front axle and showing a dirigible headlight embodying the principles of my invention in use, the view being taken looking in the direction indicated by the arrow 1 in Fig. 2.

Fig. 2 is a rear elevation of the parts 20 shown in Fig. 1 as seen looking in the direction indicated by the arrow 2.

Fig. 3 is a fragmentary side elevation of 25 one of the lamp brackets as seen looking in the direction indicated by the arrows 3 in Figs. 2 and 4, parts being shown in section.

Fig. 4 is a top plan view of the parts shown in Fig. 3 and looking in the direction indicated by the arrow.

Fig. 5 is a fragmentary detail elevation 30 of the lower end of the steering post shaft crank and showing the connection of the dirigible headlight to the shaft, the view being taken looking in the direction indicated by the arrows 5 in Figs. 2 and 6.

Fig. 6 is a detail view partly in section 35 and looking in the direction indicated by the arrow 6 in Fig. 5.

The lamp posts are usually rigidly mounted in the brackets 1 and 2 extending outwardly from the radiator 3. I remove the rigid lamp posts and substitute the swinging brackets 4 and 5. The brackets 4 and 5 are substantially alike, and in Figs. 3 and 4 I have shown the details of the bracket 5.

The bracket 2 has a vertical opening 6, a spacing washer 7 fits upon the bracket 2, a brace plate 8 fits upon the washer 7, a second and longer brace plate 9 fits upon the brace plate 8, the spacing washer 10 fits 45 upon the brace plate 9, the supporting arm 11 fits upon the brace plate 9 loosely around the washer 10, the washer being thicker than the arm, the brace plate 12 fits upon the arm 11, the brace plate 13 fits upon the brace plate 12, the bolt 14 is inserted downwardly 50 through the parts 13, 12, 10, 9, 8, 7 and 2,

and a nut 15 is placed upon the lower end of the bolt and drawn tight, and the arm 11 swings freely on the spacing washer 10 as a pivot. The brace plates 8 and 9 serve to 60 support the arm 11, and the brace plates 12 and 13 serve to hold the arm 11 down upon the plate 9.

The arm 11 has a downwardly and backwardly extending bend 16, a downwardly 65 extending straight portion 17, a backwardly extending bend 18, a downwardly extending bend 19, a backwardly extending bend 20, and a backwardly extending straight portion 21.

The brace 22 has a central opening fitting 70 loosely upon the bolt 14 and bearing against the nut 15. The rear end of the brace 22 is connected to the portion 18 by a clamping bolt 23. The lamp post 24 is inserted 75 downwardly through the forward end of the arm 11 and has a shoulder 25 resting upon the arm, there being a spacing collar 26 under the arm 11, and the reduced portion 27 of the post extends downwardly 80 through the spacing collar 26 and through the brace 22, and a nut 28 is placed upon the lower end of the post to clamp the brace 22 against the spacing collar 26 and clamp the spacing collar against the arm 11, and 85 the arm 11 against the shoulder 25 so as to make the lamp post rigid; so that by loosening the nut 28 the lamp 29 may be turned upon the vertical axis as desired to throw the light to the center of the road at a 90 proper distance in front of the vehicle, and so that the lamp may be held in its adjusted position by tightening the nut 28.

The link 30 connects the rear ends of the portions 21. The bracket 5 has an extension portion 31 extending beyond the link 30, and a draw bar 32 has a bent end 33 inserted downwardly through the portion 31. The ends of the link 30 are bent at right angles and inserted downwardly through 100 the portions 21. Springs 34 and 35 are placed upon the end of the draw bar 32 below the portion 31 and upon the end of the link 30 below the portions 21. Washers 36 and 37 are placed against the springs, and 105 coppers 38 and 39 are inserted below the washers, the tensions of the springs being exerted to hold the parts from rattling.

The draw bar 32 is connected to the steering post shaft 40, as shown in Figs. 5 and 6. 110 The steering post shaft has a crank 41 extending at right angles to the body of the

shaft, and a bearing ball 42 extending from the lower end of the crank 41. The regular draw bar 43 of the steering gear is connected to the socket plate 44 fitting half way around the ball 42, and a second socket plate 45 fits against the other side of the ball and is secured to the first socket plate 44 by bolts 46 and 47. I remove the bolts 46 and 47 and place a supplemental plate 48 against the plate 45 and then replace the bolts 46 and 47, or substitute longer bolts.

An ear 49 extends from the plate 48 and the end of the draw bar 32 is inserted loosely through the ear 49. A spring seat 50 in the form of a washer is placed upon the draw bar 32, a cotter 51 is inserted through the draw bar outside of the spring seat, a spring 52 is placed against the spring seat, a concavo-convex washer 53 is placed against the spring 52, and the draw bar 32 is inserted through the ear 49 with the convex side of the washer against the ear. A second concavo-convex washer 54 is placed upon the draw bar against the other side of the ear 49, a second spring 55 is placed against the washer 54, a second spring seat 56 is placed against the spring 55, and a second cotter 57 is inserted through the draw bar 32 so as to effectually connect the draw bar 32 to be operated by the operation of the steering post shaft 40, and so as to make a yielding connection between the steering gear of the vehicle and the lamps so that the vibration of the wheels will not vibrate the lamps.

The ear 49 preferably has a slot 58, and a hanger 59 extends downwardly from the frame bar 60, and the hanger 59 has a slot 61, so that when desired the draw bar 32 may be raised out of the slot 58 and raised and inserted into the slot 61 so as to operate the automobile without the dirigible feature of the headlights.

Thus I have produced a dirigible headlight for Ford automobiles in which the headlights may be accurately adjusted to center to and from the center of the road, and in which there is a yielding connection between the steering gear and the headlight, so that the vibration or wobble of the front wheels will not vibrate the headlights.

Various changes may be made without departing from the spirit of my invention as claimed.

I claim:

1. In combination with a vehicle having a front wheel steering apparatus, lamp brackets fixed to the vehicle frame, arms disposed across the tops of the brackets and extending forwardly and backwardly therefrom, the backwardly extending portions being bent downwardly, brace members disposed across below the lamp brackets and extending forwardly and backwardly therefrom, the backwardly extending portions being fixed to the arms, the forwardly extending portions being spaced from the forwardly extending portions of the arms and carrying, together with the arms, vertically disposed lamp holders, said arms and braces being adapted to be pivotally connected with the bracket by vertical pins, a tie rod connecting the two arms whereby the arms will be caused to move in unison, and a reach rod flexibly connecting one of the arms with the steering knuckle of the steering apparatus.

2. In combination with a vehicle having a front wheel steering apparatus, lamp brackets fixed to the vehicle frame, arms disposed across the top of the brackets and extending forwardly and backwardly therefrom, the backwardly extending portions being bent downwardly, brace members disposed across below the lamp brackets and extending forwardly and backwardly therefrom, the backwardly extending portions being fixed to the arms, the forwardly extending portions being spaced from the forwardly extending portions of the arms and carrying together with the arms a vertically disposed lamp holder, said arms and braces being adapted to be pivotally connected with the brackets by vertical pins, a tie rod connecting the two arms whereby the arms will be caused to move in unison, a reach rod connected with one of the arms and flexibly connecting, with a detachable joint, to the steering knuckle of the steering apparatus, and means for connecting the reach rod when detached from the steering knuckle to a stationary part of the vehicle whereby the lamps may be held stationary.

In testimony whereof I have signed my name to this specification.

FRANK SPONG.
